JOURNAL BOX

Edmund P. Kinne, Alliance, Ohio, assignor to
 American Steel Foundries, Chicago, Ill., a corporation of New Jersey

Application July 1, 1943, Serial No. 493,046

12 Claims. (Cl. 308—47)

My invention relates to journal boxes and more particularly to a novel journal box lid arrangement.

An object of my invention is to design an arrangement such as above described wherein the spring pressure is applied to the center of the lid for urging the same into engagement with the journal box opening to seal the same.

A different object of my invention is to provide means for equalizing the pressure of the lid against the top and bottom margins of the journal box opening.

A specific object of my invention is to design an arrangement such as above described wherein a journal box lid and an associated hood member are pivotally mounted on the journal box hinge lug, said hood being in engagement adjacent its lower end with an arcuate rib formed on the external surface of the lid, and said hood comprising a spring member secured to the inner surface thereof and bearing against an abutment surface on said lug. The hood is loosely interlocked with said rib to permit a rocking action of the lid, thereby equalizing the pressure thereof against the top and bottom margins of the journal box opening.

My invention comprehends a hood member of novel form, said member comprising a web with a central portion flanged and re-flanged at each side thereof, said re-flanged portions affording spaced coplanar abutment surfaces for engagement with the before-mentioned arcuate rib, and said re-flanged portions being formed at their upper ends with loops or bearings for the reception of an associated pivot pin, a spring member being fixed to the inner surface of the central portion of said web adjacent its lower end and extending upwardly therefrom for engagement with the journal box hinge lug.

In the drawing,

Figure 1 is a front elevation of a journal box and associated lid structure embodying my invention.

Figure 2 is a side elevation taken from the right as seen in Figure 1 with the pivot pin shown in section in the vertical plane indicated by the line 2—2 of Figure 1.

Figures 3 and 4 are sectional views taken respectively in the planes indicated by the lines 3—3 and 4—4 of Figure 1.

Describing my invention in detail, the journal box is fragmentarily indicated at 2, said box comprising a hinge lug 4 having a flat spring abutment surface 6 for a purpose hereinafter described.

The lid or cover is generally designated 8 and comprises the spaced bearings or loops 10, 10 at opposite sides of the lug 4 for pivotal connection thereto by means of the pin 12, said lid engaging the top and bottom margins of the journal box opening 14 (Figure 1) as at 16 and 18 (Figures 2 and 4). It will be understood that sufficient clearance is provided in the connection between the loops 10, 10 and the pin 12 to afford a tilting action of the lid, as hereinafter discussed, in order to equalize the pressure of said lid against the journal box.

The hood generally designated 20 comprises a web 22 having a central portion flanged at opposite sides thereof as at 26, 26 and re-flanged as at 28, 28, the re-flanged portions bearing at 30, 30 against the arcuate rib 32 formed on the exterior surface of the lid 8. It may be noted that the re-flanged portions 28, 28 of the web 22 are interlocked with said rib 32 by means of rivets 34, 34, said interlock, as clearly illustrated in Figure 4, being sufficiently loose to accommodate a rocking action of the lid 8 on its rib 32 against the re-flanged portions 28, 28 of the hood, thus permitting equalization of the pressure of the lid against the upper and lower margins of the journal box opening at the points indicated at 16 and 18.

Secured as at 36, 36 to the central portion of the web 22 against the inner surface thereof is a flat spring member 38 bearing adjacent its upper end against the spring abutment surface 6 of the journal box hinge lug 4. It may be noted that the central portion of the web 22 is flanged at the upper end thereof as at 40 to strengthen the hood, as well as to afford a cover for the spring 38 and the upper end of the lid 8. Each re-flanged portion 28 of the hood is provided with a loop or bearing 42 for the reception of the pivot pin 12, thus permitting the hood to pivot on said pin.

It will be understood that when the device is in assembled relationship, as illustrated, the spring 38 is flexed against the surface 6 of the hinge lug 4, reaction of said spring being transmitted to the hood by its connection thereto, and thence to the lid 8 by means of the bearing of the hood against the rib 32 of the cover. Thus the lid is tightly engaged with the journal box as at 16 and 18 to seal the opening 14 therein, and it will be understood that by means of the arrangement illustrated the reaction of the spring 38 is transmitted to the lid 8 approximately midway between the top and bottom thereof, said lid being permitted a rocking or tilting action by means

of the engagement of the arcuate rib 32 with the hood to permit equalized pressure of the lid against the journal box at 16 and 18.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In combination, a journal box having a hinge lug on the top thereof, an opening in the front of said box, a hood comprising a web with a central portion flanged and reفلanged at each side thereof, said reفلanged portions of said web having loops at opposite sides of said lug, a lid having bearings at opposite sides of said loops, a pin extending through said lug, said bearings, and said loops, said lid and said hook being afforded independent pivotal movement on said pin, a flat spring housed within said hood and fixed to said central portion, said spring bearing adjacent its upper end against said lug and being flexed thereagainst, and a connection between said hood and said lid, said connection including an arcuate rib on said lid for engagement with spaced coplanar abutment surfaces on said reفلanged portions, and rigid means fixed to said hood and loosely interlocked with said lid to afford a rocking action thereof by means of said rib, whereby pressure of said lid is equalized against abutting portions of said box defining the top and bottom margins of said opening, said central portion having a flange at its upper extremity overlying said spring to afford a cover therefor.

2. In a hood for a journal box lid, a web having a central portion flanged and reفلanged at each side thereof, the reفلanged portions of said web presenting substantially coplanar bearing surfaces adjacent the lower end thereof for abutment with said lid, each of said reفلanged portions being formed at its upper end with a bearing for reception of an associated pivot pin, a flat spring fixed to the central portion of said web adjacent the lower end thereof and extending upwardly therefrom for engagement with a hinge lug on an associated journal box, and a flange on the top of said central portion overlying the upper end of said spring to afford a cover therefor.

3. In combination, a journal box having an opening in the front thereof and a hinge lug on the top thereof, a hood comprising a web with a central portion flanged and reفلanged at opposite sides thereof, the reفلanged portions of said web having loops at opposite sides of said lug, a lid having bearings at opposite sides of said loops, a pin extending through said lug, said bearings, and said loops, a spring fixed to said hood and flexed against said lug, and a connection between said hood and said lid, said connection including an arcuate surface on said lid for engagement with said reفلanged portions, and rigid means fixed to said hood and loosely interlocked with said lid to afford a rocking action thereof on said surface whereby pressure of said lid against the top and bottom margins of said opening is equalized.

4. A journal box and cover assembly comprising in combination a hinge lug on the box, a hood member having a web with a central portion flanged and reفلanged at each side thereof, the reفلanged portions of said web being pivoted to the

hinge lug, spring means reacting against the hood member and the lug for biasing said cover assembly to its closed position, a lid member loosely interlocked with the hood member, and surfaces on the reفلanged portions of said hood member bearing against cooperating surfaces of said lid member, the surfaces on one of said members being crowned.

5. In a journal box lid assembly, a journal box having a hinge lug, a lid loosely pivoted to said lug, resilient means flexed against said lug, and means for transmitting reaction of said spring to said lid for urging the same to closed position, said last-mentioned means comprising a hood member comprising a web with a central portion flanged and reفلanged at opposite sides thereof, the reفلanged portions of said web being pivoted from said lug, said hood member being loosely interlocked with said lid, and said reفلanged portions bearing against an arcuate rib formed on said lid to afford equalized pressure of said lid against abutting portions of said box.

6. In a hood for a journal box lid, a web having a central portion flanged and reفلanged at each side thereof, the reفلanged portions of said web presenting substantially coplanar bearing surfaces adjacent the lower end thereof for abutment with said lid, each of said reفلanged portions being formed at its upper end with a bearing for reception of an associated pivot pin, and a flat spring fixed to the central portion of said web adjacent the lower end thereof and extending upwardly therefrom for engagement with a hinge lug on an associated journal box.

7. In combination, a journal box having a hinge lug on the top thereof, an opening in the front of said box, a hood member having a web with a central portion flanged and reفلanged at each side thereof, the reفلanged portions of said web being pivoted to said lug, a lid member pivoted to said lug for pivotal movement with respect thereto independently of said hood member, and resilient means flexed against said lug and reacting against said hood member for urging said reفلanged portions against said lid member, whereby the latter is moved to closed position with respect to said opening, the contacting surfaces on one of said members being crowned, whereby pressure of said lid member is equalized against the top and bottom margins of said opening.

8. A journal box and a cover assembly comprising in combination a hinge lug on the box, a hood member having a web with a central portion flanged and reفلanged at opposite sides thereof, said hood member being pivoted to the hinge lug, spring means reacting against the hood member and the hinge lug for biasing said cover assembly to its closed position, a lid member loosely interlocked with the hood member, and surfaces on the reفلanged portions of said hood member bearing against cooperating surfaces of said lid member, the surfaces on one of said members being crowned.

9. In a hood for a journal box lid, a web having a central portion flanged and reفلanged at each side thereof, the reفلanged portions of said lug presenting bearing surfaces adjacent the lower extremity thereof for abutment with said lid, each of said reفلanged portions being formed at its upper end with a bearing for reception of an associated pivot means, and a spring carried by said central portion for engagement with a hinge lug on an associated journal box.

10. In a hood for a journal box lid, a web hav-

ing a central portion flanged and reflanged at each side thereof, the reflanged portions of said lug presenting bearing surfaces adjacent the lower extremity thereof for abutment with said lid, each of said reflanged portions being formed at its upper end with a bearing for reception of an associated pivot means, and a spring carried by said central portion for engagement with a hinge lug on an associated journal box, said central portion having a flange at its upper extremity overlying said spring to afford a cover therefor.

11. In a hood for a journal box lid, a web having a central portion flanged and reflanged, the reflanged portions of said web presenting substantially coplanar bearing surfaces adjacent the lower end thereof for abutment with said lid, each of said reflanged portions being formed at its upper end with pivot means, resilient means con-

nected to the central portion of said web and projecting therefrom for engagement with a hinge lug on an associated journal box, and a flange on the top of said central portion overlying said resilient means to afford a cover therefor.

12. In a hood for a journal box lid, a web having a central portion flanged and reflanged at each side thereof, the reflanged portions of said web presenting substantially coplanar bearing areas adjacent the lower extremity thereof for abutment with said lid, each of said reflanged portions being formed at its upper extremity with pivot means, and resilient means connected to the central portion of said web and extending therefrom for engagement with a hinge lug on an associated journal box.
